[57] CLAIM

The ornamental design for an air handling apparatus, as shown and described.

DESCRIPTION

FIG. 1 is a perspective view of an air handling apparatus that embodies the principles of the invention;

FIG. 2 is a front elevation view of the air handling apparatus as shown in FIG. 1;

FIG. 3 is a top view of the air handling apparatus as shown in FIG. 1;

FIG. 4 is a side elevation view of the air handling apparatus as shown in FIG. 1, the opposite side being a mirror image of that shown; and,

FIG. 5 is a rear elevation view of the air handling apparatus as shown in FIG. 1.
